Prindle and Dear, his Atty.

UNITED STATES PATENT OFFICE.

CHAUNCEY D. WOODRUFF, OF TOLEDO, OHIO.

IMPROVEMENT IN EAVES-TROUGHS.

Specification forming part of Letters Patent No. 154,537, dated August 25, 1874; application filed July 8, 1874.

To all whom it may concern:

Be it known that I, CHAUNCEY D. WOODRUFF, of Toledo, in the county of Lucas and in the State of Ohio, have invented certain new and useful Improvements in Eaves-Troughs; and do hereby declare that the following is a full, clear, and exact description thereof, reference being had to the accompanying drawing, making a part of this specification, in which—

Figure 1 is a perspective view of an eaves-trough suspended by my improved brace. Fig. 2 is a cross-section of the same through the center of said brace; and Figs. 3 and 4 are plan views of the upper and lower sides, respectively, of said brace.

Letters of like name and kind refer to like parts in each of the figures.

My invention is an improvement upon a method of suspending eaves-troughs for which Letters Patent No. 10,606 were granted to me upon the 7th day of March, 1854; and it consists, principally, in a brace or bar constructed of or from two corrugated strips of sheet metal, and having each of its ends tenoned and divided horizontally, substantially as and for the purpose hereinafter specified. It consists, further, in the means employed for securing the lower portion of the suspension-rod to or upon the roof, substantially as and for the purpose hereinafter shown.

In the annexed drawing, A represents an eaves-trough, provided, at suitable intervals along its upper side, with cross-bars or braces B and B', and suspended from a roof, C, by means of suspension-rod E and E, that are secured to or upon the upper side of the latter, and, extending outward and downward, are connected to or with said braces, as in my patent before named. In order that the braces B and B' may have the necessary rigidity, and may be capable of easy and durable attachment to the trough A, the former are formed of two plates of metal, B and B', which are correspondingly arched longitudinally and transversely, are placed closely together, and the projecting edges b and b' of the upper plate,

B, are then turned inward over the edges of the lower plate. Each end of each plate B and B' is provided with a tenon, b', which, when the bar is ready for use, lie closely together, but, when in use, said tenons are passed outward through a slit, a, in the eaves-trough A, and are then turned upward and downward, as seen in Fig. 2, against the outer face of said trough, when they are, preferably, soldered in place.

I am aware that tenoned braces composed of a single plate have before been attached to or upon a trough by passing said tenons through the sides of the latter and turning them upward in the form of a hook, and, therefore, do not claim such construction.

In order that the suspension-rod E and E may be rigidly attached to the roof, so as to prevent longitudinal and vertical motion of the eaves-trough, I take a strip of sheet metal, F, of suitable size, fold the same together around each rod, and through its united ends drive a nail, f, into said roof.

This method of attaching the rod is effective, simple, and inexpensive, and materially increases the strength and durability of the trough.

Having thus fully set forth the nature and merits of my invention, what I claim as new is—

1. The brace or bar B, composed of two corrugated and joined metal plates, provided with tenoned ends that are divided horizontally and combined with the eaves-trough A, in the manner and for the purpose substantially as specified.
2. In combination with the suspension-rod E and E, the clips F and F, constructed in the manner and for the purpose substantially as shown.

In testimony that I claim the foregoing I have hereunto set my hand this 16th day of June, 1874.

CHAUNCEY D. WOODRUFF.
